SPOTLIGHT

Application filed July 5, 1929. Serial No. 375,970.

My invention relates to lamps, and more particularly to a novel form of photographic spot-light such as is used in the motion-picture industry.

Spot-lights at present used in this industry are very bulky and are relatively difficult to move from place to place.

It is an object of my invention to provide a rigid spot-light of light weight having desirable optical characteristics.

10 A further object of my invention is to provide a lamp having a large radiating surface for dissipating the heat generated by the light source therein.

15 Still a further object of the invention is to provide a novel lamp structure in which all noises due to the expansion of the parts have been eliminated, thus preventing the extraneous noises so objectionable in the making of talking pictures.

20 A further object of the invention is to provide a photographic lamp which will not form dark rings near the outer portion of the leak-light diverging from the main beam.

25 These and other objects I accomplish by the use of a corrugated reflector bounding the light chamber and separating this chamber from the surrounding area.

30 A further object of the invention lies in this novel corrugated reflector construction.

Further objects and advantages of this invention will be made evident hereinafter.

35 In the drawings, I have illustrated the preferred embodiment of my invention, Fig. 1 illustrating a side view of my lamp.

Fig. 2 is a cross-sectional view taken on the line 2-2 of Fig. 1.

Fig. 3 is a cross-sectional view taken on the line 3-3 of Fig. 2.

40 Fig. 4 is an enlarged fragmentary view of a portion of Fig. 3.

Fig. 5 is a diagrammatic perspective view of the lamp-adjusting mechanism of my invention.

45 The lamp of my invention comprises front and rear frames 10 and 11 respectively, which are preferably formed of cast aluminum, or a similar light-weight metal.

50 Between these frames is positioned a re-

flector 12 which is preferably formed in sections, there being a pair of corresponding side sections 13 and 14, the sides of which fit in side channels 15 and 16 formed in both frames 10 and 11. These side sections are corrugated as best illustrated in Fig. 2, the side channels 15 and 16 being of sufficient width to accommodate these corrugations.

The ends of these corrugated side sections do not meet, but are separated by chimney spaces 19 and 20 which are in vertical alignment with each other. Covering the chimney space 20 and overlapping the ends of the side sections 13 and 14 is an auxiliary corrugated reflector 21, the sides of which are mounted in an upper auxiliary channel 22 of an upper extension 23 formed on each frame. A similar auxiliary corrugated reflector 24 covers the chimney space 19 and extends in overlapping relationship with the ends of the side sections 13 and 14, this auxiliary reflector 24 fitting in a lower auxiliary channel 25 formed in a lower extension 26 of each frame. The auxiliary corrugated reflectors are separated from the side sections 13 and 14 so as to provide small spaces 28 through which air may pass.

The frames 10 and 11 are clamped against the sides of the side sections 13 and 14 and the auxiliary reflectors 21 and 24 by means of a plurality of tie rods 28a extending between these frames and providing nuts 29 threaded thereto which may be tightened to increase the clamping engagement between the frames and the corrugated members forming the reflecting surfaces. I have found that such a construction entirely eliminates noises due to the expansion of parts when heated. However, as an added precaution, I place a packing 30 in each of the channels 15, 16, 22, and 25 against which the sinuous edges of the corrugated members are pressed, this packing being preferably made of asbestos.

These tie rods also cooperate with a supporting means for the lamp, this supporting means being shown in the form of a pin 35 mounted on a strap 36 suitably secured to adjacent tie rods 28a. A plate 37 has an opening to receive the pin 35, this plate being secured to uprights 39 which are in turn secured

to a platform 40 of a tripod 41 of any suitable design. By such a construction, the lamp of my invention may be pivoted about the pins 35 and secured in any position by clamping a 5 thumb-screw 42 which may be threaded into one of the pins 35 in a manner to press the plate 37 against the strap 36.

The reflector 12 defines a light chamber 45, the rear of which is bounded by a suitable 10 mirror 46, the forward edge of which is mounted in a channel formed by an angled ledge 47 of the rear frame 11, as best shown in Figs. 3 and 4.

This rear frame also provides an annular 15 countersunk portion 49 in which the flange of a cover 50 is retained as by screws 51 passing therethrough and threaded into the rear frame 11. This cover is preferably, although not necessarily, corrugated, the corrugations 20 preferably extending concentric with the axis of the beam of the light, as best shown in Figs. 3 and 4. The mirror 46 is retained in place by spring clips 52 suitably secured to the cover and bearing against the rear surface 25 of the mirror.

Also extending between the front and rear frames 10 and 11 are rods 53 and 54, the former being in the form of a long bolt rigidly secured in place by a nut 55, and the latter 30 being threaded through at least a portion of its length and being suitably journalled in both the front and rear frames 10 and 11. A crank 57 is adapted to rotate the rod 54 to move a carriage 58 relative thereto. This 35 carriage has an arm 58a through which the rod 54 is threaded and has an arm 59 adapted to slide along the rod 53. This arrangement is best shown in Fig. 5. A suitable base 60 for a light source 61 is provided on the carriage 40 58, this light source being shown in the form of an incandescent lamp. Obviously, I am not limited to this form of light source.

Held in place by certain of the tie rods 28a and the rods 53 and 54 are retainers 63, these 45 retainers being three in number and provided for holding a screen or glass in the path of the rays transmitted from the light source 61 and reflected from the mirror 46 and the reflecting surfaces of the corrugated members.

The corrugated members, as well as the cover 50 are preferably made of aluminum, this material being not only light in weight, but having superior heat-conducting properties. Previous lamps have been extremely 55 bulky, and difficult to move from place to place. On the other hand, my invention is not only compact and occupies no unnecessary space, but is also very light in weight, 60 the weight of my lamp being substantially half the weight of certain other lamps of equivalent size at present in use, and being substantially 30% lighter in weight than the lightest weigh lamp of equivalent capacity 65 at present in use.

The corrugated members used in my lamp are a very important feature of this invention. These corrugations provide more than double the radiating surface which would be provided by an uncorrugated circular reflector plate such as is ordinarily used. With my lamp there is thus no danger of an operator becoming burned by touching the exterior thereof as is the case with other lamps having similar heat-radiating surfaces.

These corrugations find utility in my invention whether or not the inner surface thereof is brightened so as to act as a reflecting surface. In this latter capacity, however, I have found that a beam of light cast 70 by the lamp of my invention is superior to those at present used in the motion-picture industry inasmuch as no dark rings are formed in the leak-light diffused outward from the main beam. This feature is an important one in motion-picture work where even illumination is essential.

If desired, the mirror 46 may be dispensed with and the internal surface of the cover 50 may be brightened to act as a reflecting 75 surface. If corrugations are provided in this cover, the beam cast by the light will be a very diffused one. However, with the construction illustrated in the drawings, it is not essential that this cover be corrugated 80 inasmuch as the mirror 46 prevents the direct rays of the light source from reaching this cover. I have found, however, that the mirror will be kept cooler by the provision of corrugations on the cover 50.

I claim as my invention:

1. In a photographic lamp, the combination of: front and rear frames having channels therein; a pair of reflectors between said frames and having their sides in said channels, said reflectors bounding a light chamber and being separated at their upper and lower ends; a light source in said light chamber; and means for clamping said frames against said sides of said reflectors.

2. In a photographic lamp, the combination of: front and rear frames; a pair of reflectors between said frames and clamped between said frames, the ends of said reflectors being separated to form a chimney; and an auxiliary reflector clamped between said frames to cover said chimney.

3. In a photographic lamp, the combination of: a pair of frames having channels therein; corrugated reflectors fitting in certain of said channels, the ends of said reflectors being separated; and corrugated auxiliary reflectors in other of said channels in a position to cover the spaces between said first-named reflectors.

4. In a single walled lamp structure the combination of: a front frame of annular shape; a rear frame; a corrugated member between said frames and supported thereby, the corrugations of said member extending

- transversely between said frames, said corrugated member defining the boundary of a light chamber and separating said light chamber from the surrounding atmosphere whereby heat generated in said light chamber is conducted through said corrugated member and radiated into space; means for moving said frames toward each other to clamp said corrugated member rigidly therebetween, the compression set up in said corrugated member thus being along the length of said corrugations rather than transverse thereto; and a light source in said light chamber.
5. In a photographic lamp the combination of: a pair of frames; a reflector means positioned between said frames and defining a light chamber; a light source in said light chamber; and a pair of rods extending between said frames and on which said light source is movable.
6. In a photographic lamp, the combination of: a front frame; a rear frame, there being corresponding channels formed in said frames; a corrugated reflector extending between said frames and having the corrugations thereof extending transversely between said frames, the ends of said corrugated reflector extending into said channels; packing means in each of said channels and engaging the ends of said corrugated reflector to prevent any expansion noises due to a relative expansive movement of said reflector and said frames; and means for clamping said frames and said corrugated reflector together.
7. In a single-walled lamp structure, the combination of: a light source; a corrugated member defining the boundary of a light chamber in which said light source is positioned and formed of a material having a high heat conductivity, the interior of said corrugated member being directly exposed to the rays of said light source, and the exterior of said corrugated member being directly exposed to the surrounding atmosphere whereby the heat generated by said light source is radiated into space; and a rigid frame bounding said corrugated member in supporting relationship.
8. A photographic lamp including in combination a corrugated reflector having a sinuous edge; a frame providing a channel of width sufficient to receive said sinuous edge; packing means between said sinuous edge and the bottom wall of said channel; and means for forcing said corrugated reflector into said channel against said packing means.
9. In a photographic lamp, the combination of: front and rear frames each providing a pair of side channels spaced from each other and a pair of auxiliary channels one above and one below the said side channels thereof; a pair of corrugated side reflectors extending between said frames, the ends
- thereof extending into said side channels; a pair of auxiliary corrugated members extending between said frames, the ends thereof extending into said auxiliary channels; and means for securing said frames, said side reflectors, and said corrugated members together.
10. In a photographic lamp, the combination of: a pair of frames, each frame providing side and auxiliary channels therein; side wall means extending between said frames and into said side channels of said frames to define a light chamber, said side wall means providing separated ends defining a chimney space; an auxiliary enclosing member extending between said frames and into said auxiliary channels thereof and positioned in overlapping relationship with respect to said separated ends of said side wall means and spaced therefrom to permit circulation through said chimney means; packing means in said side and auxiliary channels of said end frames; and means for forcing said frames toward each other to clamp said side wall means and said auxiliary member therebetween and against said packing means.
- In testimony whereof, I have hereunto set my hand at Los Angeles, California, this 1st day of July, 1929.
- FRANK P. ARROUSEZ.
